UNITED STATES PATENT OFFICE.

JOHN E. GREENAWALT, OF NEW YORK, N. Y.

MAGNETIC SEPARATOR.

1,324,149.

Specification of Letters Patent.

Patented Dec. 9, 1919.

Application filed January 31, 1917, Serial No. 145,684. Renewed October 16, 1919. Serial No. 331,245.

To all whom it may concern:

Be it known that I, JOHN E. GREENAWALT, a citizen of the United States, residing at New York, in the county of New York and 5 State of New York, have invented certain new and useful Improvements in Magnetic Separators, of which the following is a full, clear, and exact description, reference being had to the accompanying drawings, forming 10 a part hereof.

The present invention is directed to apparatus and processes involving the utilization of magnetic fields for separating magnetic from non-magnetic particles, as for example in the magnetic concentration of ores where the magnetic ore particles or minerals are separated from the non-magnetic material with which they are associated. The invention has for its object to provide an apparatus in which the separating or concentrating process may be carried on under conditions favorable to a thorough and complete removal of the magnetic particles or minerals from the non-magnetic material.

25 In the practice of my invention use is made of the buoyant action of liquids in motion whereby they serve not only to hold in suspension the non-magnetic particles but to completely segregate the same from the 30 magnetic particles while the latter are held under the influence of the magnetic field. Specifically, the invention contemplates wet magnetic separation, that is to say, separation of magnetic particles from non- 35 magnetic particles in the presence of a current of water with which the particles are mixed and in which they are more or less suspended, forming what is generally termed pulp. In the present embodiment of

40 my invention the magnetic particles are held to the depositing or concentrating surface of an endless belt by means of a powerful magnetic field acting through the belt, the belt traveling in a given direction and carrying the magnetic particles with it to a 45 point beyond the magnetic field where the said particles are dropped, the non-magnetic particles and water of the original pulp being carried in the opposite or different 50 direction whereby the magnetic particles become completely segregated from the non-magnetic material. Concurrently with the action of the magnetic field on the magnetic particles, the belt is subjected to an agitation or reciprocating shaking movement in

a direction preferably transverse to the directions of travel of the belt and of the non-magnetic component of the pulp, whereby the separating or concentrating action is rendered more perfect and complete, such shaking movement having the effect of releasing the non-magnetic particles from the magnetic particles held fast to the belt. In the treatment as outlined above, the magnetic particles are influenced by (1) the magnetic field 60 operating through the belt or equivalent conveyer; (2) the force of gravitation tending to hold the mineral particles to the concentrating or depositing surface of the belt; (3) the continuous movement of the particles by the 65 continuous movement of the belt; and (4) the shaking or reciprocating movement of the belt which enables the water to wash away all the non-magnetic particles while the magnetic particles are held firmly 70 against the belt. On the other hand, the non-magnetic particles are influenced by (1) the force of gravitation though in a less degree than are the magnetic or mineral particles by reason of the lower specific 75 gravity of such non-magnetic particles; (2) the buoyant action of the liquid or water in which the particles are more or less suspended; (3) the shaking or reciprocating movement of the belt which freely agitates 80 the particles, the latter owing to their non-magnetic character being free to be washed away by the stream of water; (4) the carrying of the particles by the flowing stream 85 to the discharge end of the belt. The advantages of the invention will be fully apparent from the following detailed description thereof in connection with the accompanying drawings in which—

Figure 1 represents a top plan of the concentrator, parts being broken away; Fig. 2 is a side elevation thereof; Fig. 3 is a middle vertical longitudinal section on the line 3—3 of Fig. 1; and Fig. 4 is a vertical cross-section on the line 4—4 of Fig. 2.

95 Referring to the drawings, 1, 1, represent parallel structural members serving to support the U-shaped shoes or bearings 2 to which the lower ends of the oscillating links 3 are pivotally secured, the upper ends of the links being pivotally coupled to similar shoes or bearings 2' secured to the sides of an oblong frame 6 composed of suitable structural members connected by tie rods 105 t well understood in the art. Disposed on 110

one side of the frame 6 near each end thereof are pairs of lugs or ears 7 between which are pivotally secured the inner terminals of suitable eccentric rods 8 the straps 9 whereof 5 pass around the eccentrics 10 on the main drive shaft 11 mounted parallel to the longitudinal axis of the frame 6, said shaft 11 being actuated from any suitable source of power (not shown). From the connections 10 described the frame 6 has imparted to it short transverse reciprocations or a shaking motion, the supporting links 3 oscillating in vertical planes during these reciprocations. Mounted in suitable bearings at each end of 15 the shaking frame 6 are drums or large pulleys 12, 12', respectively over which passes a continuous or endless concentrator belt 13 provided with a concentrating or depositing surface bounded by marginal 20 flanges *a*, the said concentrating surface inclining downward somewhat from the drum 12 toward the drum 12', to permit the water to carry off to better advantage the non-magnetic material which has been separated 25 from the magnetic particles. This inclination should be but slight (as shown in the drawings) in order to prevent a too rapid flow of the water over the depositing surface, thereby allowing the non-magnetic 30 particles ample time to detach themselves from the magnetic particles under the shaking action of the belt. By thus reducing the rate of flow of the water over the depositing surface we bring about the accumulation of 35 a maximum or substantial quantity of pulp receiving the benefit of the shaking action aforesaid. Motion is imparted to the belt by a worm shaft 14 mounted in the bracket arms 15 carried by the frame 6, the worm 40 pinion 16 on said shaft meshing with a worm wheel 17 on the shaft 18 of the drum 12. Rotation at any desired speed may be imparted to the shaft 14 from any convenient source, preferably however from the 45 shaft 11 by means of a belt 19 passing over a cone pulley 20 on the shaft 11 and over a similar cone pulley 21 on the shaft 14. The direction of travel of the concentrating belt 13 is from the drum 12' toward the drum 50 12, the latter drum dipping into a body of water in a tank 22 which receives the concentrates dropped from the belt at that end. At the opposite end the tailings or non-magnetic particles and water with which 55 they are mixed are received in a tailings tank or receptacle (or launder) 23, the material flowing over the drum 12' directly into the receptacle. The lower lap of the 60 concentrating belt 13 passes over guide rollers 24 disposed below the frame 6, and supported in brackets or hangers 25 carried by said frame as clearly shown in the drawings. These rollers are sufficiently elevated to cause the ends of said lower lap to incline 65 downward or dip toward the tanks 22, 23, respectively, said dip being desired to properly guide the belt lap across the tanks (Fig. 3). The upper lap of the concentrator belt is supported on rollers 26 mounted on side bars 27 carried by the blocks 28 at 70 each end of the frame 6, said rollers being of iron or steel or equivalent material having a high magnetic permeability, the side bars 27 however being of non-magnetic material such as wood to prevent the short circuiting of the lines of force between the positive and negative poles of the magnets operating in conjunction with the concentrator belt as will hereinafter more fully appear. 75

Disposed at the terminals of the I-beams or structural members 1, are suitable structural members or I-beams 29 to which are secured the posts or standards 30, said posts being well within the frame 6 and removed 80 sufficiently from the sides thereof so as not to interfere with the shaking movements of the frame. To the upper terminals of said standards are secured the angle beams 31, the connection being effected by means 85 of angle brackets 32 or otherwise (that is immaterial) as best appeals to the skilled mechanic. The horizontal legs of the angles 31 serve to support the yokes 33 of a series of powerful electromagnets 34 (although 90 permanent magnets are not outside the scheme of my invention) the poles of which are presented to the bottom surface of the upper lap of the concentrator belt, the magnets being confined between the belt laps 95 as shown. The poles N, S, of the magnets are alternately positive and negative (that is, to say north and south poles) in order that the lines of force may be distributed to the best advantage throughout the entire 100 magnetic field. In order to accommodate the rollers 26 the several poles of the series of magnets are formed with longitudinal 105 grooves or depressions *d*, a sufficient clearance being left between the rollers and walls 110 of the depressions to permit of the shaking movement necessarily participated in by the rollers without rubbing against the poles. The pulp is delivered onto the concentrating 115 surface of the belt from a perforated pipe 35 disposed transversely across the middle of the belt close to the concentrating surface, one end of the pipe being closed, the opposite end being adapted to be coupled to any suitable source of pulp supply 120 (not shown). Between the pulp-feed pipe 35 and the drum 12 and near the end of (but still within) the magnetic field is a similar cross pipe 36, said pipe serving to spray 125 water onto the belt so as to thoroughly wash the concentrates or magnetic particles adhering thereto before said particles pass out of the influence of the magnetic field. 130

The operation is obvious from the foregoing description, but briefly stated is sub-

stantially as follows: Rotation being imparted to the drive shaft 11 in proper direction, the upper lap of the concentrator belt will be advanced from the drum 12' 5 toward the drum 12 so as to permit the concentrates to drop from the concentrating surface into the concentrate tank 22. At the same time the frame 6 and necessarily the concentrator belt will have imparted to them 10 a series of quick transverse reciprocations or shaking movements as already described. These shaking movements operate to loosen the non-magnetic from the magnetic particles, which latter tend to separate themselves from the non-magnetic not only on 15 account of the higher specific gravity of said magnetic particles (minerals and metals usually have a higher specific gravity than the gangue or rock with which they are associated) but on account of being drawn to and held against the concentrating surface by the action of the magnetic field operating through the belt. By the time the magnetic particles carried by the belt reach 20 the drum 12 they will have passed outside or beyond the influence of the magnetic field, being left free to drop from the belt into the tank 22, the water in said tank washing the particles off the belt before the 25 lower lap passes over the drum 12'. The shaking movement imparted to the frame 6 and to the concentrator belt causes a thorough and quick separation of the non-magnetic component of the pulp from the magnetic 30 particles adhering to the belt, said non-magnetic component flowing down the incline of the concentrating surface of the belt into the vat or tank 23, so that a complete segregation of the magnetic from the 35 non-magnetic particles results. The pulp as it is delivered to the belt assumes the form of a sheet, said sheet freely flowing toward the drum 12' from which the tailings (non-magnetic component of the pulp) flow directly 40 into the vat or tank 23. The magnetic particles of course begin to adhere to the belt the moment the pulp strikes the concentrating surface thereof and will be carried with the belt under the spray pipe 36 45 at which point they will be thoroughly washed before dipping into the water in the concentrate tank 22. I do not of course wish to be restricted to the details here shown or to the direction or kind of shaking motion 50 imparted to the belt. Features shown but not alluded to are well understood in the art and a description thereof is unnecessary.

Having described my invention what I claim is:

60 1. In an apparatus of the character described, a suitable conveyer provided with a concentrating surface, means for spreading thereover in sheet form a charge of liquid pulp containing magnetic and non-magnetic particles, a magnetic field operat-

ing to hold the magnetic particles against the concentrating surface whereby they advance with the conveyer, the concentrating surface being pitched or inclined to the horizontal to cause the non-magnetic particles to flow in the opposite direction to the travel of the conveyer, said pitch being sufficiently low to materially retard the passage of the pulp along the concentrating surface and retain thereon a body of pulp 70 of substantial depth, and means for subjecting the conveyer to agitation during the period of its travel whereby the non-magnetic particles suspended in the water of the pulp are released from the magnetic particles adhering to the concentrating surface. 75

2. In combination with a frame, an endless belt conveyer mounted thereon and having an upper lap traveling in a plane slightly inclined to the horizontal, the upper face 80 of said lap serving as a depositing or concentrating surface for a charge of liquid pulp, the pitch of said surface being sufficiently low to materially retard the passage of the pulp thereover and retain thereon a body of pulp of substantial depth, means 85 for imparting motion to the belt, means for imparting to the frame and belt a series of shaking movements or reciprocations transverse to the direction of travel of the belt, 90 rollers disposed across the bottom of the upper lap of the belt for supporting the same, and a series of electro-magnets disposed beneath and adjacent to said upper lap, the poles of said magnets being provided with 95 suitable grooves or depressions for receiving the lower peripheral portions of said rollers, the latter being composed of material having magnetic permeability. 100

3. In an apparatus of the character described, a suitable conveyer provided with a concentrating surface pitched or inclined to the horizontal, means for delivering thereto a charge of liquid pulp containing magnetic and non-magnetic particles, the 105 pitch of the concentrating surface being sufficiently low to materially retard the passage of the pulp thereover and retain thereon a body of pulp of substantial depth, a magnetic field operating to hold the magnetic particles against the concentrating surface 110 whereby they travel with the conveyer, and means for causing a disengagement of the non-magnetic particles from the magnetic particles adhering to said surface. 115

4. In an apparatus of the character described, a suitable conveyer provided with a concentrating surface, means for spreading thereon a charge of liquid pulp containing magnetic and non-magnetic particles, a magnetic field operating through the conveyer to hold the magnetic particles against the concentrating surface whereby they advance with the conveyer, the concentrating surface being pitched or inclined to the hori- 120 125 130

zontal, said pitch being sufficiently low to materially retard the passage of the pulp along the concentrating surface and retain thereon a body of pulp of substantial depth, 5 and means for subjecting the conveyer to agitation during the period of its travel whereby the non-magnetic particles suspended in the water of the pulp are released and caused to flow away from the magnetic

particles adhering to the concentrating sur- 10 face.

In testimony whereof I affix my signature, in presence of two witnesses.

JOHN E. GREENAWALT.
